UNITED STATES PATENT OFFICE

JOSEPH D. McNUTT, OF NEW HAVEN, CONNECTICUT, ASSIGNOR, BY MESNE ASSIGNMENTS, TO WINCHESTER REPEATING ARMS COMPANY, A CORPORATION OF MARYLAND

PRIMING MIXTURE

No Drawing.

Application filed October 5, 1927. Serial No. 224,281.

My invention relates to an improvement in priming mixture, the object being to produce a priming mixture of such a character that it will leave no corrosive residuum.

3 With these ends in view, my invention consists in a priming mixture characterized by the employment, as an oxygen-supplying element of a metallic chromate, either alone or in admixture with another oxidizing substance, preferable a metallic peroxid; as fuel element, a nitrated organic compound; and as detonating element, a metallic fulminate.

10 A suitable priming mixture may be formed, for instance, of mercury fulminate, tetranitroanilin and lead chromate in the following proportions:

	Per cent
Lead chromate-----	35 to 45
Mercury fulminate-----	30 to 40
20 Tetranitroanilin-----	10 to 15
Ground glass-----	0 to 20

25 The proportions of these ingredients may be varied, the mercury fulminate and tetranitroanilin being used substantially within the limits specified above, and the lead chromate being used in sufficient quantity to supply the necessary oxygen to burn the tetranitroanilin, or other fuel, as will be understood by those skilled in the art.

30 However, I preferably employ, dependent upon the commercial strength of the ingredients, substantially:

	Per cent
35 Mercury fulminate (dry weight)-----	25 to 40
Lead peroxid-----	20 to 40
Barium chromate-----	5 to 10
Tetranitroanilin-----	3 to 15
Ground glass-----	15 to 25

40 though these proportions may be varied as may be necessary to meet the requirements of various uses of the ultimate mixture.

45 In proceeding to make my improved priming mixture, the peroxid, chromate, tetranitroanilin and ground glass are weighed out, sifted and mixed dry. A small portion of a solution of gum is now added and mixed in. The fulminate in a dampened state is then weighed out and added to the above mixture, and the whole, after being thor-

oughly mixed, is then used in the ordinary manner of such priming mixtures.

I also find that I may use other heavy metal oxides or nitrates such as barium dioxid or nitrate in place of the lead peroxid and 55 I may substitute chromates of mercury for barium chromate or lead chromate. Also I may substitute trinitroresorcinol or other suitable nitrate organic substance in whole or in part for the tetranitroanilin. Such 60 substitutions, in whole or in part, fall within the scope of my invention.

I claim:

1. A priming mixture, comprising 20% to 40% of lead peroxid, 5% to 10% barium 65 chromate, 25% to 40% of mercury fulminate, and 3% to 15% tetranitroanilin.

2. A priming mixture, comprising 20% to 40% of lead peroxid, 5% to 10% barium chromate, 25% to 40% of mercury fulminate, 70 3% to 15% tetranitroanilin, and 15% to 25% ground glass.

In testimony whereof I affix my signature.
JOSEPH D. McNUTT.
